RECLINING CHAIR

Frank D. Hoffman, Jr., High Point, N. C., assignor to General Steel Products Company, Inc., High Point, N. C., a corporation of North Carolina

Application March 10, 1954, Serial No. 415,216

8 Claims. (Cl. 155—105)

This invention relates to reclining chairs and more particularly to reclining chairs having leg rests whose movement is coordinated with the movement of the chair into reclining position.

Many types of reclining chairs have been developed in which a leg rest member is moved upwardly as the reclining chair is moved into reclining position. Most of these chairs have the leg rest member pivotally connected to the forward portion of the chair seat and a linkage means is provided for moving the leg rest member upwardly about its pivot point when the chair is moved into reclining position. One limitation of chairs operating upon the principle just mentioned is the fact that the leg rest member, being pivotally connected at one of its ends to the seat member, does not project as far forwardly of the chair as might be desired for the comfort of the occupant of the chair.

Accordingly, it is an object of this invention to provide a reclining chair having a leg rest which is supported by an operating linkage, rather than being pivotally connected to the front of the chair seat as is common in many types of reclining chairs.

It is another object of this invention to provide a reclining chair structure in which a leg rest member is projected upwardly and forwardly of the seat by the motion of the chair seat or seat-back structure into reclining position.

In achievement of these objectives, this invention provides a reclining chair in which a leg rest is connected to a pair of pivotally interconnected lever members which are moved upwardly and forwardly of the chair when the chair is moved into reclining position. In one embodiment of the invention the leg rest is supported at spaced points by the outer ends of the pivotally interconnected levers. One of the lever members is pivotally connected to one of the chair members and is acted upon by an actuating link connected to the other chair member. The other lever member is connected to a guiding link which is connected at its opposite end to the same chair member to which the first lever is pivotally connected. In another embodiment of the invention, a further amplification of the movement of the leg rest is attained by connecting first and second auxiliary lever members to the outer ends of the respective members constituting the pair of levers and then connecting the outer ends of the auxiliary levers to spaced points on the leg rest member.

Other objects and advantages will become apparent from the following description taken in connection with the accompanying drawing in which:

Fig. 1 is a view in sectional side elevation of a reclining chair in accordance with the invention showing diagrammatically the position occupied by the leg rest and its operating mechanism when the chair is not in reclining position;

Fig. 2 is a view of the chair of Fig. 1 showing diagrammatically the position assumed by the leg rest and its operating mechanism when the chair is in reclining position;

Fig. 3 is a perspective view of the leg rest and its operating mechanism corresponding to the diagrammatic view shown in Fig. 2; and

Fig. 4 is a perspective view, similar to Fig. 3, showing the position assumed by a leg rest having a modified form of operating mechanism, with the chair in reclining position.

Referring now to the drawing, and more particularly

2

to Figs. 1-3, there is shown a reclining chair generally indicated at 10 having a stationary supporting framework 12 and a unitary seat-back structure 15 which includes a seat 14 and a back 16. In the embodiment shown, the seat and back are rigidly connected together and move as a unit. A horizontally extending member 18, which is preferably of metal construction, is rigidly attached to the supporting structure 12 and extends lengthwise or in the front-rear dimension of the chair.

10 The seat-back structure 15 is pivotally movable about the stationary supporting structure 12 by means of a link member 20 which is rigidly connected to the seat 14 at point 22, adjacent the rear portion of the seat. Link 20 is pivotally connected to the member 18, and hence to the supporting structure 12, at point 24. A leg rest member 26 is disposed at the front portion of the chair and, when the chair is not in reclining position, as shown in Fig. 1, the leg rest member 26 assumes a vertical position. A bracket member 28 is rigidly attached to the underneath portion of the leg rest and lies in a plane which is parallel to the plane of the leg rest.

In order to coordinate the movement of the leg rest with the movement of the seat-back structure, a connecting linkage is provided between the seat-back structure 15 and the leg rest 26 which will now be described. In the embodiment shown in Figs. 1-3, this linkage includes the bracket 28 and the links 30, 32, 34, 36, 38, 40 and 42. Link or lever member 32 is pivotally connected to the stationary supporting framework at point 44 which is located at the forward portion of the member 18. At its outer end, the member 32 is pivotally connected at point 46 to an end of link or auxiliary lever member 38 which, in turn, is pivotally connected at its opposite end at point 48 to a portion of the bracket member 28 which is disposed at the rear of the bracket 28 when the leg rest is in elevated position.

In the position shown in Fig. 1, the pivot point 48 is at the upper extreme of the bracket 28 with the leg rest in vertical position. Link or lever member 36 is pivotally connected to link 32 at point 50 which is intermediate the lengths of both link members 32 and 36. The lower end of link 36, with respect to the view shown in Fig. 1, is pivotally connected to an end of guide link 42 at point 52. The opposite or upper end 45 of guide link 42 is pivotally connected at point 54 to the stationary member 18 which is attached to the supporting framework 12. The upper end of link 36 with respect to the view shown in Fig. 1 is pivotally connected to an end of link or auxiliary lever 34 at point 56. The opposite end or lower end of link 34, with respect to the view shown in Fig. 1, is pivotally connected to an end of link 40 at point 58. The opposite end of link 40 is pivotally connected to the bracket 28 at point 60, which is positioned below the pivot point 38, with respect to the view shown in Fig. 1.

Link 34 is connected intermediate of its length to link 38 at point 62, this connection also being intermediate the length of member 38. The upper end of the link or lever 32 is provided with an extension or rigidly attached crank arm 33 which extends substantially at right-angles to the longitudinal axis of the link 32 adjacent the pivotal connection 44 or link 32 to the stationary framework. Actuating link 30 is pivotally connected at point 35 to the forward portion of the seat 14. It will be seen that the rigid connection of crank arm 33 to lever 32 forms in effect a bell crank in which the short arm of the bell crank is formed by crank arm 33 while the long arm of the bell crank is formed by lever 32. The opposite end of the actuating link 30 is pivotally connected at point 37 to the crank arm 33, at a position which is laterally spaced from the longitudinal axis of the link 32.

It can be seen that the links 32, 34, 36 and 38, because of their pivotal interconnections at points 50, 46, 56 and 62, form what may be termed a closed primary quadric linkage or closed quadrilateral linkage which, in the embodiment shown in Fig. 1, is substantially a parallelogram in shape. Furthermore, the link 34, the bracket 28, and the links 38 and 40 form a second closed quadric linkage which is also substantially in the shape of a parallelogram.

When the chair seat 14 is moved into reclining position, as shown in Figs. 2 and 3, the pivotal movement of the chair seat about its pivot point 24 is communicated to the leg rest operating mechanism through the connection of actuating link 30 to the crank arm 33 attached to link 32. The upward movement of link 30 causes the link 32 and its attached lever member 33 to be swung upwardly about its pivot point 44 to approach a horizontal position as shown in Figs. 2 and 3. The upward movement of link 32 about its pivot point 44 raises the link 36 which is pivotally connected to link 32 at point 50. Link 42 moves upwardly about its pivot point 54 because of its pivotal connection at 52 to link 36. As the links 32, 42 and 36 move upwardly, the link 36 swings about its pivotal connection 50 to link 32 in such manner that the interior angle subtended by links 36 and 32 changes from an obtuse angle, as in the case of the vertical position of the leg rest shown in Fig. 1, to an acute angle in the extended position of the leg rest shown in Figs. 2 and 3. Because of the constrained linkage interconnection between links 36, 38, 32 and 34, the movement imparted by link 42 to link 36 is also communicated to the other links in the primary quadric linkage formed by links 32, 34, 36 and 38 in such manner as to shift the links 36 and 38 in a forward direction. As a result of the forward shifting of the links 34, 36 and 38, the point of pivotal support 48 of the bracket 28 and of the leg rest 26 is also shifted forwardly. In order to limit the upward movement of the leg rest, a stop member 64 is provided in the path of movement of the link 42, the stop member 64 being attached to the member 18 which is a part of the stationary framework of the chair.

The forward and upward shifting movement of the leg rest 26 is still further amplified by the secondary quadric chain composed of the links 34, 38, 40 and the bracket 28. The interconnection between these links at the pivot points 48, 62, 58 and 60 causes the link 40 to pivot forwardly about its pivot point 58 and causes a forward shifting of the bracket 28 to aid in projecting the leg rest still further forwardly of the chair.

There is shown in Fig. 4 a modified embodiment of the invention which is similar to the embodiment shown in Figs. 1 to 3 except that the secondary quadric linkage is not used. Thus, the embodiment of Fig. 4 includes the actuating link 30' which is pivotally connected at 37' to the crank arm 33' of lever or link 32'. The leg rest 26' is supported by bracket 28'. Links 32', 36', 38' and bracket 28' together form a primary quadric linkage which is substantially in the shape of a parallelogram. Links 36' and 38' are pivotally connected to bracket 28' at the pivot points 56' and 62', respectively. An end of link 38' is pivotally connected to an end of link 32' at point 46'. Links 32' and 36' are pivotally connected to each other at point 50'. The ends of links 36' and 42' are pivotally connected together at point 52'. The guide link 42' is pivotally connected to the supporting framework at 54'. A stop member 64' projects from the surface of the member 18' attached to the stationary framework of the chair in order to limit the motion of the guide link 42'. The operation of the linkage of the embodiment of Fig. 4 is the same as that previously described for the embodiment of Figs. 1-3; that is, the pivotal motion of the seat member 14' is communicated through actuating link 30' to the lever or link 32' which is raised to a substantially horizontal position as shown in Fig. 4. At the same time, the connection of the guide member 42' to the link 36' causes a forward motion of the quadric linkage formed by the links 32', 28', 36' and 38' in such manner as to shift the leg rest 26' in a forward direction.

It can be seen from the foregoing that there is provided in accordance with this invention a simple and efficient mechanism for shifting a leg rest upwardly and forwardly of a reclining chair as the chair seat is moved into reclining position.

While there have been shown and described particular embodiments of the invention, it will be understood by those skilled in the art that various changes and modifications may be made therein without departing from the invention and it is aimed in the appended claims to cover all such changes and modifications as fall within the true spirit and scope of the invention.

What I claim as my invention is:

1. A reclining chair comprising a reclining member

supported by a stationary member, a leg rest disposed at the front of said chair for movement upwardly and forwardly of said chair, a pair of levers pivotally connected to each other intermediate their ends, an actuating link pivotally connected to one of said levers and to one of said members, said one lever being pivotally connected to the other of said members at a point spaced from the pivotal connection between said one lever and said actuating link, a guiding link pivotally connected to the other of said levers at a point spaced from the pivotal connection between said levers, said guiding link being pivotally connected to said other member, and means swingably connecting one end of each lever to said leg rest at spaced points.

2. A reclining chair comprising a reclining member supported by a stationary member, a leg rest disposed at the front of said chair for movement upwardly and forwardly of said chair, a pair of levers pivotally connected to each other intermediate their ends, one of said levers including a crank portion adjacent one of its ends, an actuating link pivotally connected to said crank portion and to one of said members, said one lever being pivotally connected to the other of said members at a point spaced from the pivotal connection between said crank portion and said actuating link, and a guiding link pivotally connected to the other of said levers at a point spaced from the pivotal connection between said levers, said guiding link being pivotally connected to said other member, and means swingably connecting one end of each lever to said leg rest at spaced points thereon.

3. A reclining chair comprising a reclining member supported by a stationary member, a leg rest disposed at the front of said chair for movement upwardly and forwardly of said chair, a pair of levers pivotally connected to each other intermediate their ends, a bell crank having a long arm formed by one of said levers and a short arm, an actuating link pivotally connected to the short arm of said bell crank and to one of said members, said bell crank being pivotally connected to the other of said members at a point spaced from the pivotal connection between said actuating link and said short arm of said bell crank, a guiding link pivotally connected to the other of said levers at a point spaced from the pivotal connection between said levers, said guiding link being pivotally connected to said other member, and means swingably connecting one end of each lever to said leg rest at spaced points thereon.

4. A reclining chair comprising a reclining member supported by a stationary member, a leg rest disposed at the front of said chair for movement upwardly and forwardly of said chair, a pair of levers pivotally connected to each other intermediate their ends, an actuating link pivotally connected to one of said levers and to one of said members adjacent the forward portion of said member, said one lever being pivotally connected to the other of said members at a point spaced from the pivotal connection between said one lever and said actuating link, a guiding link pivotally connected to the other of said levers at a point spaced from the pivotal connection between said levers, said guiding link being pivotally connected to said other member, and means swingably connecting one end of each lever to said leg rest at spaced points thereon.

5. A reclining chair comprising a reclining member supported by a stationary member, a leg rest disposed at the front of said chair for movement upwardly and forwardly of said chair, a pair of levers pivotally connected to each other intermediate their ends, an actuating link pivotally connected to one of said levers and to one of said members, said one lever being pivotally connected to the other of said members at a point spaced from the pivotal connection between said one lever and said actuating link, a guiding link pivotally connected to the other of said levers at a point spaced from the pivotal connection between said levers, said guiding link being pivotally connected to said other member, and an auxiliary lever pivotally connected to the outer end of said one lever and to said leg rest, an end of said other lever being pivotally connected to said leg rest.

6. A reclining chair comprising a reclining member supported by a stationary member, a leg rest disposed at the front of said chair for movement upwardly and forwardly of said chair, a first and a second lever pivotally connected to each other intermediate their ends,

an actuating link pivotally connected to said first lever and to one of said members, said first lever being pivotally connected to the other of said members at a point spaced from the pivotal connection between said first lever and said actuating link, a guiding link pivotally connected to said second lever at a point spaced from the pivotal connection between said levers, said guiding link being pivotally connected to said other member, a first auxiliary lever connected to the outer end of said first lever, a second auxiliary lever pivotally connected to the outer end of said second lever, said first and second auxiliary levers being pivotally connected to each other intermediate their ends, and means swingably connecting the outer end of each of said auxiliary levers to said leg rest at spaced points thereon.

7. A reclining chair comprising a reclining member supported by a stationary member, a leg rest disposed at the front of said chair for movement upwardly and forwardly of said chair, a first and a second lever pivotally connected to each other intermediate their ends, said first lever including a crank portion adjacent one of its ends, an actuating link pivotally connected to said crank portion and to one of said members, said first lever being pivotally connected to the other of said members at a point spaced from the pivotal connection between said crank portion and said actuating link, a guiding link pivotally connected to said second lever at a point spaced from the pivotal connection between said levers, said guiding link being pivotally connected to said other member, a first auxiliary lever pivotally connected to the outer end of said first lever, a second auxiliary lever pivotally connected to the outer end of said second lever, said first and second auxiliary levers being pivotally connected to each other intermediate their ends, and means swingably connecting one end of each auxiliary lever to said leg rest at spaced points thereon.

8. A reclining chair comprising a reclining member supported by a stationary member, a leg rest disposed at the front of said chair for movement upwardly and forwardly of said chair, a first and a second lever pivotally connected to each other intermediate their ends, a bell crank, said bell crank having a long arm formed by said first lever and a short arm, an actuating link pivotally connected to said short arm of said bell crank and to one of said members, said bell crank being pivotally connected to the other of said members at a point spaced from the pivotal connection between said actuating link and said short arm of said bell crank, a guiding link pivotally connected to said second lever at a point spaced from the pivotal connection between said levers, said guiding link being pivotally connected to said other member, a first auxiliary lever pivotally connected to the outer end of said first lever, a second auxiliary lever pivotally connected to the outer end of said second lever, said first and second auxiliary levers being pivotally connected to each other intermediate their ends, and means swingably connecting one end of each auxiliary lever to said leg rest at spaced points thereon.
